UNITED STATES PATENT OFFICE.

EVERETT R. KAYLOR, OF QUINCY, ILLINOIS.

GRAIN SHOCKER.

Application filed March 12, 1927. Serial No. 174,799.

The object of this invention is to provide a grain shocker which may be attached to any standard grain binder in position to receive the bundles of grain as they pass from the binder deck, and may be easily operated to gather the bundles into a shock and then deposit the shock upon the ground with their heads uppermost. The invention seeks especially to provide a shocker which will be simple in construction and operation and easily manipulated by the driver from the seat of the binder and which, when attached to the binder, will not add perceptibly to the draft. These stated objects of the invention, and other objects which will incidentally appear in the course of the following description, are attained in such an apparatus as is illustrated in the accompanying drawings, and the invention resides in certain novel features which will be particularly pointed out in the appended claims.

In the drawings:

Figure 1 is a perspective view of a shocker embodying my invention, the shocker being shown in its proper relation to a binder, a portion of which is indicated in dotted lines;

Fig. 2 is a side elevation of the shocker showing the same in an intermediate position as the shock is being transferred to the ground;

Fig. 3 is a similar view showing the shocker in position to release the shock;

Figs. 4 and 5 are detail elevations showing different positions of the shock-engaging fingers;

Fig. 6 is a detail section, and

Fig. 7 is a transverse section on the line 7—7 of Fig. 2.

In carrying out the invention, I provide a main frame, indicated at 1, which may be of any suitable form and is illustrated as consisting of parallel side rails connected by a cross bar at their front ends, the space between the rear ends of the side bars or rails being left open for the passage of the shock. The outer rail 1 is equipped with a caster 2 whereby it may be supported for ready travel over the field and to the inner side rail are secured beams 3 which are hingedly connected, as indicated at 4, to the said rails and extend to the binder frame to which they are secured firmly in any convenient or preferred manner. Braces 5 may be provided to reinforce these attaching arms, as will be understood. Near the rear ends of the side rails 1 a cranked rock shaft or arch

6 is journaled therein, the greater portion of the length of said shaft being formed into the arch 7 and adapted to carry a supplemental frame 8 while the ends of the shaft are formed into cranks 9 which are disposed substantially at a right angle to the sides of the arch and to which are attached the rear ends of tension springs 10 which have their front ends attached to screws 11 mounted in brackets 12 at the front ends of the side rails whereby the tension of the springs may be easily regulated. Secured to and extending between the side rails are a series of bars or rods 13 which are in the form of inverted arches and define arcs, the radii of which increase successively from the rear to the front of the frame, these bars or rods forming a cradle to receive the bundles passing from the deck of the binder. The butts of the bundles will be directed toward the front, and a guard 14 of any suitable form may be secured to the front cross bar of the main frame so as to prevent the bundles slipping from the cradle.

The supplemental frame comprises two side bars, preferably of flat metal construction, connected at their front and rear ends by cross bars 15 of similar form. The arch 7 is journaled in the side bars of the frame 8 at about the center thereof and bearing brackets 16 are preferably secured to the side bars so as to provide an additional support for the arch to prevent bending of the same under the strains to which it is subjected in use. Adjacent the centers of the cross bars 15 and at opposite sides of the center and equi-distant therefrom, frame bars 17 are secured thereto and extend longitudinally of the frame above the arch. The extremities of these frame bars 17 are turned downwardly, as shown at 18, to provide supports for carrying rods 19, and upon these carrying rods are loosely mounted heads 20 carrying the shock-engaging and clasping fingers 21. Each head 20 is provided with a laterally extending lug 22 and a retractile spring 23 is attached at its opposite ends to the said lug and to the immediately adjacent frame bar 17, as shown in Fig. 1 and as will be understood. Upon reference to Figs. 2 and 3, it will be noted that the fingers 21 define arcs of different radii, the fingers having the shortest radii being disposed at that end of the supplemental frame or shock carrier which is at the rear in the position assumed when the

shock is being raised. This formation adapts the fingers to the tapered form of the shock and maintains that form as the shock is being transferred from the cradle to the ground, the pressure exerted by the fingers serving to bind the bundles into a shock of a tapered or substantially conical form so that the butts will be spread and the heads brought together to cause the shock to stand upright on the ground without the necessity of additional securing devices. Attached to each head 20 at a point at the rear of the arch 7 is a rocking arm 24 which is fitted about the respective fulcrum rod 19, as indicated at 25, whereby it may be rocked on said rod, and above the rod the arm is shaped to extend outwardly and then upwardly, as clearly shown in Fig. 7. To the upper end of each arm 24 is pivoted one end 20 of a link 26, the two links being pivoted together, as indicated at 27, whereby the links and arms together constitute toggles disposed at opposite sides of the center longitudinal plane of the supplemental frame or carrier. At a point in advance of the vertical plane of the toggles, a rod 28 is secured upon and extends between the frame bars 17 and between said frame bars a guide roller or pulley 29 is rotatably mounted thereon, a cable 30 being attached at one end to the pivot 27 of the links 26 and extending thence to and about the roller 29 and then to the front of the machine where it may be trained through any suitable guides to a point adjacent the driver's seat. The heads 20 are rotatable and also slideable upon the fulcrum rods 19, and it will be seen that with the carrier frame in the position shown in Fig. 1 and the toggles in the position shown in full lines in Fig. 7, a pull exerted upon the cable 30 will cause the pivot 27 to move downwardly in a straight line so that the lower ends of the links 26 will move outwardly and spread apart, the arms 24 being thereby rocked about the rods 19 so that the fingers 21 will be swung together to clasp the shock, the position of the fingers after this movement being indicated by dotted lines in Fig. 7. To maintain the fingers in shock-engaging position, the free end of the cable may be secured in any obvious manner adjacent the driver's seat, but it will be observed that, when the fingers are fully closed, the pivot of the links 26 will be below a line passing through the upper ends of the arms 24 and, therefore, the end of the cable may be left free, provided care be observed to so support it that it will not drop to the ground or be carried to a point where it cannot be conveniently reached for a subsequent operation.

Disposed about the rear ends of the fulcrum rods between the lugs 18 and the adjacent ends of the heads 20 are expansion springs 31 which tend constantly to main-

tain the heads in the forward or lowered position illustrated in Figs. 1, 2 and 4. Extending between the rear ends of the heads 20 is a loop 32 shown most clearly in Fig. 6 in which is engaged one end of a link 33 which has its other end pivotally attached to an angle arm or striker 34, said angle arm or striker being hung upon the rod 28 and being so disposed as to extend across the path of the links 26. Mounted upon the front cross bar of the main frame is a rock shaft 35 from which rises a lever or crank arm 36 in the central longitudinal plane of the apparatus and to the said crank arm at the upper extremity thereof and at a point below its extremity, respectively, are pivoted connecting rods or links 37 and 38, the link 37 being pivotally engaged about the arch 7 and the link 38 being engaged about the rod 28 in a similar manner. The rock shaft 35 extends to a point over the binder frame where it may be conveniently reached by the driver and is equipped with a crank or pedal, indicated at 39.

In operation, the machine will travel over the field at the stubble side of the binder and will be disposed so that the delivery edge of the binder deck is immediately over the cradle. The bundles will pass from the binder deck into the cradle and will be permitted to collect therein until enough bundles have been formed to make a shock, the carrier frame and shock-engaging fingers being, during this period, supported substantially in the position shown in Fig. 2 with the fingers, however, spread apart, as shown in full lines in Fig. 7. When enough bundles have been collected to form a shock, the shaft 35 is actuated to swing the lever or crank arm 36 forward, thereby causing the carrier frame to move forward and the arch 7 to rock about the shaft 6 as a center, the cranks 9 being simultaneously swung rearwardly and the springs 10 put under increased tension. When the carrier or supplemental frame has been thus brought to a position directly over the collected bundles, a pull is exerted upon the cable 30 and the toggles thereby folded and swung into the positions illustrated by the dotted lines in Fig. 7, bringing the fingers 21 into position about the shock and compressing the bundles so that they will be firmly held by said fingers. This movement of the fingers will swing the lugs 22 downwardly so that the springs 23 will be placed under increased tension but they will be inactive inasmuch as the pivot 27 will be past the line connecting the pivotal connections of the links and the arms 24. In other words, the links are on a dead center and will not move unless a positive actuating force is applied thereto. The shock having been engaged by the fingers 21, the pivot or crank 39 is permitted to swing rearwardly so that the springs 10

will be free to act and swing the cranks 9 forwardly, thereby rocking the arch 7 upwardly and rearwardly so that the shock will be lifted from the cradle and carried to a 5 point in rear of the same. The lever 36, of course, will simultaneously swing rearwardly and through the connections of the links or rods 37 and 38 will swing the carrier frame from the substantially horizontal position 10 shown in Figs. 1 and 2 to the vertical position shown in Figs. 3, 4 and 5. The shock will thus be turned from a horizontal position to a vertical position with its butts presented to the ground and the turning of the arch 15 7 will be continued until the shock strikes the ground and for an instant after the contact of the shock with the ground, the weight of the carrier and the shock causing the arch to swing rearwardly and downwardly after 20 the springs 10 have contracted to their shortest dimension. The impact of the shock upon the ground will be transmitted to the fingers 21 and through the same to the heads 20 so that the heads will move upwardly 25 relative to the frame bars 17 and the springs 31 will be thereby placed under compression. This relative upward movement of the heads will be sufficient to release the fingers from the shock but will not effect opening of the 30 fingers. The upward movement of the heads, however, will be transmitted through the link 33 to the striker 34 and will cause the striker to impinge against the pivotally connected ends of the links 26 and move them 35 sufficiently to carry them beyond the line passing through the connections of the links to the arms 24, whereupon the springs 23 will at once contract and return the parts 40 to the positions illustrated by the full lines in Fig. 7. The fingers will then be entirely free of the shock and the springs 10 will actuate the arch 7 through the cranks 9 to return the carrier from the position shown in Fig. 3 to that shown in Fig. 2, the driver 45 pressing upon the pedal 39 so as to effect the desired turning of the carrier or supplemental frame about the arch, as will be understood.

From the foregoing description, taken in 50 connection with the accompanying drawings, it will be seen that I have provided a very simple mechanism whereby the bundles of grain may be quickly gathered into a shock and deposited upon the ground at the rear 55 of the machine as the machine is drawn over the field. The mechanism is free of complicated arrangements and eliminates unnecessary parts so that it may be readily connected to any type of grain binder without 60 adding perceptibly to the draft of the machine. The operation of the shocker is at all times under the complete control of the driver of the machine so that the likelihood of premature or delayed operation of the 65 gathering fingers and removal of the shock

is overcome. The shock-engaging fingers are constructed of resilient metal so that it will not be necessary for a specified number of bundles to be collected in order to form a shock as, within reasonable limits, the fingers will automatically conform to the diameter of the shock, the ends of the fingers overlapping sufficiently to accommodate spreading due to a shock containing one or more bundles more than the average while 70 the curvature of the fingers is such that they will firmly engage a shock containing a few number of bundles. 75

Having thus described the invention, I claim:

1. A grain shocker comprising a cradle, means for attaching the cradle to a binder frame in position to receive bundles from the binder, an arch spanning the cradle and having its sides journaled in the sides of the 80 cradle to rock longitudinally thereof, a supplemental frame mounted on the arch for relative rocking movement and normally held thereby over the cradle, heads disposed longitudinally of the supplemental frame, 85 shock-engaging fingers carried by the heads, means for engaging the fingers about bundles in the cradle and for releasing the fingers when the bundles are to be discharged, means for rocking the arch whereby to dispose the supplemental frame over the cradle or at the rear of the same, and means for turning the supplemental frame about the arch as the arch is rocked. 90

2. A grain shocker comprising a main 100 frame, a cradle in the main frame, a rock shaft mounted in the frame and having its intermediate portion formed into a normally upstanding arch spanning the cradle and provided with cranks at its ends, retractile 105 springs secured to said cranks and to the frame at points in advance of the cranks, a carrier mounted upon the arch for relative rocking movement, heads mounted upon the carrier, shock-engaging fingers on the heads, 110 means on the carrier for engaging the fingers about a shock or releasing them therefrom, and means connected with the carrier for turning the same as the arch is rocked.

3. A grain shocker comprising a cradle 115 to receive bundles from a binder, a carrier supported from the cradle to assume a position over the cradle or a position at the rear thereof, a rock shaft mounted upon the front of the frame, a lever rising from said shaft, 120 links pivotally connected to said lever at spaced points and extending rearwardly therefrom and connected to the carrier at spaced points whereby the carrier will be turned from a horizontal position to a vertical 125 position as it moves from over the cradle to the rear thereof, shock-engaging fingers mounted on the carrier, and means on the carrier to engage the fingers about a shock or release them therefrom. 130

4. A grain shocker comprising a carrier, means for swinging the carrier from a shock-engaging position to a shock-delivery position, rocking heads mounted longitudinally 5 on the carrier, fingers carried by said heads to engage and support a shock, arms secured to the heads and extending upwardly therefrom, links pivotally connected to said arms and to each other, means for moving the 10 links in one direction to engage the fingers about a shock, and means for moving the links and arms in the opposite direction and releasing the fingers from a shock.
5. A grain shocker comprising a carrier, 15 means for moving the carrier from a shock-engaging position to a shock-delivery position and vice versa, heads mounted on the carrier for rocking movement, arms extending upwardly and outwardly from the heads, 20 fingers carried by the heads, links pivoted to the arms and to each other, springs acting on the heads and tending constantly to hold the fingers in open position, means for swinging the links to a position between the arms 25 whereby to close the fingers and maintain them in the closed position, and means actuated by delivery impact of a shock to move the links beyond the arms whereby to open the fingers.
- 30 6. A grain shocker comprising a carrier, means for moving the carrier from a shock-engaging position to a shock-delivery position and vice versa, heads mounted on the carrier for relative rocking and sliding movement, fingers carried by the heads, arms secured to the heads and extending upwardly and outwardly therefrom, links pivoted to the arms and to each other, means for yieldably holding the heads in one position on the

carrier, springs connected with the heads and the carrier and tending constantly to close the fingers, means connected with the links to spread the same and the arms whereby to close the fingers, a striker mounted on the carrier in position to impinge against the 40 links, and a connection between the striker and the heads whereby delivery impact of a shock will effect relative sliding movement of the heads and cause the striker to impinge against the links to move them outwardly 45 50 and permit the springs to open the fingers.

7. A grain shocker comprising a cradle, a carrier mounted to move between a position over the cradle to a position at the rear thereof, means on the carrier to gather bundles in 55 the cradle into a shock, and means actuated by impact of the shock upon the ground to release the last-mentioned means.

8. A grain shocker comprising a cradle, a carrier, a rocking support for the carrier arranged to dispose the carrier over the cradle or in rear thereof, means for rocking the carrier as it moves from over the cradle to the rear thereof, bundle-engaging means on the carrier, and means actuated by impact 60 65 of the bundles on the ground to release the bundle-engaging means.

9. A grain shocker comprising a carrier, means for moving the carrier from a bundle-engaging position to a bundle-delivering position, means on the carrier to engage and support bundles, said means being movable relatively upward upon impact of the bundles upon the ground, and means actuated by 70 75 said upward movement to release the bundle-engaging means.

In testimony whereof I affix my signature,
EVERETT R. KAYLOR. [L. S.]
